US00D453570S

(12) United States Design Patent **(10) Patent No.:** **US D453,570 S**
Grenier **(45) Date of Patent:** **** Feb. 12, 2002**

(54) CASING FOR RADIATION SOURCE

5,418,379 A 5/1995 Parsons et al. 250/497.1

(75) Inventor: **Steven J. Grenier, Arlington, MA (US)**

* cited by examiner

(73) Assignee: **AEA Technology QSA Inc.,**
Burlington, MA (US)

Primary Examiner—Stella Reid

(74) Attorney, Agent, or Firm: Wolf, Greenfield & Sacks, P.C.

(**) Term: **14 Years**

(57) CLAIM

(21) Appl. No.: **29/131,079**

The ornamental design for a casing for radiation source, as shown and described.

(22) Filed: **Oct. 13, 2000**

DESCRIPTION

(51) LOC (7) Cl. **24-01**
(52) U.S. Cl. **D24/158**
(58) Field of Search **D24/158; 250/250,**
250/497.1, 496.1, 493.1-495.1, 498.1; 378/62

FIG. 1 is a perspective view of the outer casing according to the present invention;
FIG. 2 is a front view of the outer casing of FIG. 1;
FIG. 3 is a rear view of the outer casing of FIG. 1;
FIG. 4 is a top view of the outer casing of FIG. 1;
FIG. 5 is a bottom view of the outer casing of FIG. 1;
FIG. 6 is a left side view of the outer casing of FIG. 1; and,
FIG. 7 is a right side view of the outer casing of FIG. 1.
The broken lines are for illustrative purposes only and from no part of the claimed design.
